Primary Examiner — Cynthia R Underwood

(74) Attorney, Agent, or Firm — Mark D. Miller

(57) **CLAIM**

I claim the ornamental design for a rope securing device, as shown and described.

DESCRIPTION

FIG. 1 is a top plan view of a rope securing device showing my new design;

FIG. 2 is a bottom plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top perspective view thereof; and,

FIG. 8 is a bottom perspective view thereof.
